UNITED STATES PATENT OFFICE

136,578

DESIGN FOR A GAUGE

Ray R. Reed and Jarl W. Hanson, Duluth, Minn.

Application December 9, 1942, Serial No. 108,990

Term of patent 14 years

To all whom it may concern:

Be it known that we, Ray R. Reed and Jarl W. Hanson, citizens of the United States, residing at Duluth, in the county of St. Louis and State of Minnesota, have invented a new, original, and ornamental Design for a Gauge, of which the following is a specification, references being had to the accompanying drawing, forming part thereof.

Fig. 1 is a top plan view of a gauge, showing our new design.

Fig. 2 is a bottom plan view of Fig. 1.

Fig. 3 is an elevational view of the handle end of the instrument, and

Fig. 4 is a section on the line 4—4, on Fig. 2.

We claim:

The ornamental design for a gauge, substantially as shown.

RAY R. REED.
JARL W. HANSON.
